HOOK AND EYE

Louis La Rocca, 149 S. Poplar Ave., Maple Shade, N.J.

Filed July 10, 1958, Ser. No. 747,719

1 Claim. (Cl. 24—227)

The present invention relates to the hook and eye assembly that is ordinarily employed to establish a quickly detachable connection between two parts of a garment and is concerned primarily with what might be called a heavy duty hook and eye. A hook and eye of this particular type is ordinarily employed to close the gap at the top of the fly in trousers. It is characterized as including a wide or heavy hook of sheet metal and an eye of comparable size.

At the present time it is the common practice to mount a hook on one flap of the trousers at a distance spaced inwardly from the edge thereof. This arrangement presents difficulty in accurately locating the hook and also in correcting any errors when it has been mislocated. Thus, with the now known arrangements, once a hook has been secured in position in the trouser flap considerable difficulty is experienced in relocating it.

With this thought in mind, an important object of the invention is to provide a new and improved hook which is highly simplified and which is particularly adapted for location at the edge of the trouser flap. The hook comprises a comparatively long backing plate and a short bill with the two being spaced apart and joined by a bend. The backing plate is adapted for insertion between the two plies of a trouser flap at the edge thereof and is provided with two or more holes intended for cooperation with anchoring means. While it is entirely possible to employ stitching in conjunction with these holes, the invention has particularly in mind the use of a metallic fastener in the nature of a staple.

The eye that is now meeting with widespread if not substantially universal use, consists essentially of an eye bar having pointed tangs or flanges at each end together with an anchoring bar formed with slots which receive these pointed tangs and which is positioned on the inner face of the garment fabric to which the eye is applied. The pointed tangs pierce the fabric, pass through the slots, and are clinched by being turned inwardly.

This arrangement has presented considerable difficulty and inconvenience in that after a garment has been finished the eye bar is pressed or clinched so closely to the anchoring bar that a separate operation is required to separate the two sufficiently to permit the insertion of the bill of the hook. Moreover, this condition is often recreated when the garment is pressed during usage.

Another important object of the invention is to provide a new and improved eye which is characterized as including the conventional eye bar and an anchoring bar. However the latter is of a novel arrangement whereby the two are laterally offset so that there is a space or gap between the eye bar and anchoring bar which is occupied only by the fabric of the garment. Thus, definite assurance is had that the bill of the hook may always be easily inserted.

More in detail, the invention has as an object the provision, in a hook and eye assembly of the character aforesaid, of an anchoring bar for the eye which has laterally offset lobes at each end which are formed with

2

the slots which receive the pointed tangs on the eye bar. These tangs are clinched by being bent outwardly against the lobes rather than inwardly as has been the practice heretofore.

- 5 Various other more detailed objects and advantages of the invention such as arise in connection with carrying out the above noted ideas in a practical embodiment will in part become apparent and in part be hereinafter stated as the description of the invention proceeds.
- 10 For a full and more complete understanding of the invention reference may be had to the following description and accompanying drawing herein.

Figure 1 is a view in front elevation of two flaps of a garment, such as a pair of trousers, and are intended to be closed by the hook and eye of this invention. In this view, one of the flaps is turned outwardly for purposes of illustration.

Figure 2 is a detailed perspective showing the two elements of the eye in exploded relation;

- 20 Figure 3 is a detailed perspective of the hook per se;
- Figure 4 is a transverse section through the eye and garment part to which it is attached, being taken about on the plane represented by the line 4—4 of Figure 1;
- Figure 5 is a view in elevation looking at the inner side of the ply of the garment to which the eye is attached, being taken about on the plane represented by the line 5—5 of Figure 4;

- 25 Figure 6 is a detailed section taken normal to the showing of Figure 4 and about on the plane represented by the line 6—6 of Figure 4;

Figure 7 is a section through the hook and garment part to which it is attached, being taken about on the plane represented by the line 7—7 of Figure 1;

- 30 Figure 8 is a view in elevation looking at the inner side of the ply of the garment part to which the hook is attached, being taken about on the plane represented by the line 8—8 of Figure 7;

- 35 Figure 9 is a section through the hook taken normal to the showing of Figure 7 and is taken about on the plane represented by the line 9—9 of Figure 8;

Figure 10 is a sectional view through the hook and eye when assembled in holding relation; and

- 40 Figure 11 is another sectional view through the hook and eye when assembled, being taken normal to the showing of Figure 10 and about on the plane represented by the line 11—11 of Figure 10.

Referring now to the drawings and first, more particularly, to Figure 1, two flaps of a garment which are intended to be closed by the hook and eye of this invention are shown in 10 and 11. These flaps may be those parts which define the fly in a pair of trousers, but this is merely exemplary of any two garment elements which are to be joined in a quickly detachable manner by a heavy duty hook and eye.

45 The hook is referred to in its entirety by the reference character H, and is applied to the flap 11. The eye, which is referred to in its entirety by the reference character E, is applied to the flap 10.

Referring now more particularly to Figure 3 wherein the hook H is illustrated per se, it will be noted that the hook H comprises a backing plate 12 of an elongate tapered side construction having a free edge at 13. Closely adjacent to this free edge 13 the plate 12 is formed with a pair of apertures 14. Integrally joined to the opposite end of the backing plate 12 by a bend 15 is a bill

50 16. The bend 15 provides for a spaced relation between the bill 16 and that part of the backing plate which it overlies. This spaced relation is identified by the gap at 17. Entering into both the bill 16 and backing plate 17 from the bend 15 is a notch or recess 18.

55 Referring now more particularly to Figures 7, 8, and 9, the garment flap 11 is shown as comprising two plies,

namely an outer ply 19 and an inner ply 20. At the free or selvage edge, both of the plies are turned inwardly as indicated at 21. Ordinarily a piece of reinforcing fabric, shown at 22, is also positioned between the two plies.

The hook H is assembled on the flap 11 by passing the backing plate through a gap or unstitched portion that is left at the selvage edge. This backing plate 12 assumes a position between the two plies 19 and 20 with the reinforcing fabric 22 being spaced between the ply 20 and the plate 12. In accordance with the preferred embodiment of the invention, a metallic fastener in the nature of a staple is then applied to anchor the hook in position. This metallic fastener is shown at 23 and includes pointed legs 24 which pierce the ply 20, reinforcing fabric 22, and then pass through the openings 14. The ends of the legs are then clinched by being bent inwardly against the backing plate as shown at 25 in Figures 8 and 9.

Referring now more particularly to Figure 2, the eye is shown as comprising an anchoring bar that is referred to in its entirety by the reference character A, and an eye bar that is identified generally as B. The anchoring bar A includes a main body or back portion 26 having an outer curved edge at 27 and an inner straight edge at 28. Integrally joined to the opposite ends of the main body portion and extended laterally inwardly from the ends of the edge 28 are lobes 29 formed with slots 30. It is important to note that these slots 30 are offset laterally with respect to the inner edge 28 of the main body portion of the anchoring bar.

The eye bar proper comprises a main body portion or back 31 to each end of which is integrally joined an end flange or leg 32 which terminates in a pointed tang 33. These tangs are intended for insertion through the slots 30 and clinching by being bent outwardly against the lobes 29.

Referring now more particularly to Figures 4, 5, and 6, the garment flap 10 is shown as comprising an outer ply 34 in an inner ply 35. Inasmuch as the eye E is to be anchored to the outer ply 34, a piece of reinforcing fabric, shown at 36, is inserted between the two plies. The anchoring bar A is positioned between this reinforcing fabric 36 and the inner ply 35. After this anchoring bar has been so positioned the eye bar B is assembled by causing the pointed tangs 33 to pierce the ply 34 and reinforcing fabric 36 and then pass through the slots 30. The ends of the tangs are then clinched by being bent outwardly against the lobes 29 as shown at 37. When

so positioned, the back 31 of the eye bar B is offset laterally with respect to the main body portion 26 of the anchoring bar A as represented by the gap 38 shown in Figure 1. This space 38 is occupied only by the fabric and will offer no appreciable resistance to the insertion of the bill 16 beneath the back 31 of the eye bar B as shown in Figures 10 and 11. Thus, no spreading operation is ever required to assure that the eye will always be in condition to receive the hook.

10 While a preferred and specific embodiment of the invention is hereinbefore set forth, it is to be clearly understood that the invention is not to be limited to the exact constructions, arrangements and designs illustrated and described because various modifications of these details may be provided in putting the invention into practice within the purview of the appended claim.

What is claimed is:

20 In a heavy-duty hook-and-eye assembly, an eye comprising an anchoring bar and an eyebar adapted to be positioned on the opposite faces of a garment to which the eye is secured, said anchoring bar being of sheet metal and of U shape defined by a pair of spaced lobes and a main body portion integrally joined to said lobes, said body portion having inner and outer edges with said lobes being offset inwardly with respect to said inner edge, said lobes having confronting edges with each of said lobes being formed with a slot normal to and spaced laterally from said inner edge and closely adjacent to one of said confronting edges, said eyebar consisting of a back extending over the space between said lobes and with a lug integrally joined to each end of said back by a bend and terminating in a pointed tang adapted to be passed through one of said slots and clinched outwardly against the respective lobe in metal-to-metal engagement therewith, each of said lobes having an extent away from the slot therein at least equal to the length of the tang passing through that slot.
